J. D. HILLIARD

ELECTRIC SWITCH

Filed June 23, 1922

Fig. 1.

Fig. 2.

Inventor:
John D. Hilliard,
by *Albert Davis*
His Attorney.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed June 23, 1922. Serial No. 570,394.

My invention relates to electric switches and in particular to means for preventing burning at the contacts when the switch is closed under load.

5 In systems of electrical distribution of power and particularly in circuits normally carrying great amounts of power at high pressure, automatic means are often employed to cut out of the system a branch or 10 feeder upon the occurrence of the fault therein. If the fault is of considerable magnitude it often happens that the burden is removed from the system near the point of generation. In such systems automatic 15 means are usually employed to restore pressure to the line after a definite time in which the faulty feeder should be isolated by the opening of the feeder circuit breaker. If the means provided for the opening of the 20 faulty feeder circuit breaker have failed and the fault persists in the feeder, the reclosing of the main circuit breaker will instantly permit a flow of current through the contacts of the circuit breaker which is largely limited merely by the capacity of the generator and the nature of the fault.

This initial rush of current is often greatly in excess of the current flowing when the circuit breaker opens upon the occurrence 30 of the fault.

Many switches heretofore designed for this service have operated satisfactorily in the matter of carrying and rupturing such circuits but have failed when called upon to 35 close the circuit upon low resistance short circuits because of the severe burning of the contacts at such closure the current densities often becoming high enough to cause welding of the contacts. In such switches the circuit is made and finally ruptured at secondary 40 contacts which for several reasons are not capable of continuously carrying the rated load of the switch.

One of the objects of my invention has 45 therefore been to provide in a switch of this character a means for preventing excessive burning of the contacts upon closure of the switch.

Another object of my invention is to provide 50 in a switch of this character a set of auxiliary contacts which will make the circuit upon closing the switch, such contacts having sufficient capacity to handle short circuit currents upon closing but said contacts not being required to make the final

break in the circuit when the switch is opened.

A further object of my invention is to provide in a switch of this character auxiliary contacts for making the circuit when the switch is being closed, said contacts having renewable burning tips which may be readily applied thereby prolonging the life of the switch, reducing to a minimum the time required to make renewals and consequently increasing the continuity of service.

Other objects and advantages of my invention will appear from the following description taken in connection with the accompanying drawings, wherein Fig. 1 is an external view partly in elevation and partly broken away of the fluid tank and contact mechanism of a single pole switch embodying the preferred form of my invention, and Fig. 2 is a view taken on the line 2—2 in Fig. 1.

In the drawing will be seen a fluid tank or receptacle 10 with an insulated lining 11 adapted to contain an insulating fluid 12, the normal level of which is indicated by the shading. A cover 15 for the fluid tank is provided with apertures to receive insulating bushings 16 for the stationary electrodes 17 of the switch, the bushings being held in place by clamping rings 18. An aperture is also provided in the tank cover 15 to allow the passage of a contact supporting rod 20 through the packed bushing 21. A metallic explosion chamber casing 25 in which the circuit is ruptured upon opening of the switch is attached to the stationary electrode 17 and is in electrical connection therewith. This explosion chamber is adapted to contain a movable secondary contact 26 having a renewable burning tip 27. Electrical connection between the secondary contact 26 and the explosion chamber casing 25 is maintained by the lead 28. Movement of the secondary contact 26 is limited by a support 30 and contact with a secondary contact stud 40 is maintained within this limit by the compression spring 29. Tertiary contact levers 31 are pivoted to lugs 32 on the outside of each of the explosion chamber casings 25 and are provided with renewable burning tips 33. Dash pots 35 are formed on the outside of each of the explosion chamber casings 25, the plungers 36 of which are connected to the levers 31 by the pins 37. The dash pot

plunger 36 is provided with valved openings so that its speed may be regulated by the resistance which the plunger offers to passage of fluid through these openings. 5 Electrical connection between the tertiary contact lever 31 and the explosion chamber casing 25 is maintained by the lead 34.

The secondary contact stud 40 is provided with a renewable burning tip 41 and is attached to a bridging member 45 and enters the explosion chamber through an insulating bushing 46. A lead 47 forms the electrical connections between the secondary contact studs. 10

15 A substantially stationary contact brush 50 is attached to the explosion chamber casing 25 and together with the tertiary contact lever 31 makes contact with a main bridging member 51 which is attached to the 20 rod 20.

The sequence of operation from the closed position of the switch is as follows: Manual or automatic tripping of operating means (not shown, but which may be similar to that 25 shown in patent to Emmet and Hewlett, 942,491, December 7, 1909) will cause the rod 20 to move downwardly and to separate the main bridging member 51 from the stationary contact brush 50. Further movement of the contact rod 20 will cause separation of the main bridging member 51 from the tertiary contact tip 33, movement of which to follow the main bridging member is impeded by action of the dash pot plunger 36. 30

35 In the meantime the secondary contact 26 has followed the downward movement of the secondary contact stud 40 by the action of the spring 29 and with further movement of the contact rod 20 will reach its limit of 40 travel against the support 30 after which the circuit will be finally opened upon parting of the burning tips 27 and 41. The circuit will be ruptured in the explosion chamber by the quenching of the arc formed upon the 45 separation of the burning tips 27 and 41 in the usual manner employed in this type of switch structure.

As the pressure created in the explosion chamber by the arc formed by the separation 50 of the contact tips 27 and 41 is released and as the fluid passes through the valved openings in the piston 36 the tertiary contact lever 31 will fall to its lower position indicated by the dotted lines.

55 In closing, the operating means will cause the contact rod 20 to rise, first making contact between the main bridging member 51 and the burning tips 33 of the tertiary contact lever 31, after which contact will be made between the secondary contact tips 27 and 41, and finally between the main bridging member 51 and the stationary contact brush 50.

From the above it will be seen that the embodiment of my invention provides a switch 60

in which the circuit is ruptured by the separation of the secondary contacts in the manner usually employed but in which these contacts are not required to sustain the burden of closing the circuit, the circuit being closed at the tips of the tertiary contact lever. As the closing contacts are not used in rupturing the circuit they may be made sufficiently rugged to withstand the severe burning which will take place when the switch is closed on short-circuit and being made renewable the life of the switch is greatly increased.

While the preferred embodiment of my invention is substantially as shown in Figs. 80 1 and 2, that is, applied to switches of the fluid break type, the same principles may as readily be applied to air break switches and to other forms of electrical apparatus. I therefore do not wish to be limited to the 85 particular structure shown.

This application is a continuation in part of my prior application, Serial No. 548,155, filed March 30, 1922.

What I claim as new and desire to secure 90 by Letters Patent of the United States, is:—

1. In a switch, a receptacle adapted to contain an insulating liquid, means forming an explosion chamber within said receptacle, a pair of contacts located within said explosion chamber adapted to break a circuit and a second pair of contacts connected in shunt with said first contacts and adapted to make said circuit within said liquid. 95

2. In a switch, a receptacle adapted to contain a liquid, means forming an explosion chamber within said receptacle, a pair of contacts adapted to break a circuit within said explosion chamber, a second pair of contacts within said receptacle connected in shunt with said first contacts and adapted to make said circuit and a single means for operating both pairs of contacts. 100

3. A switch having a pair of contacts adapted to break a circuit, a second pair of contacts in shunt relation with said first contacts adapted to make said circuit and a single means for operating both pairs of contacts. 110

4. A switch having a pair of contacts adapted to break a circuit and a second pair of contacts adapted to make said circuit, one contact of one of the pairs of contacts being rigidly connected to a contact of the other of said pairs. 115

5. A switch having a pair of contacts adapted to break a circuit and a second pair of contacts adapted to make said circuit, one contact of one of the pairs of contacts being rigidly connected to a contact of the other of said pairs and movable therewith. 125

6. A switch having a primary set of contacts arranged to carry continuously a full load current flowing through a circuit, a secondary set of contacts, a tertiary set of 130

contacts and means whereby said circuit is broken at said secondary contact and made at said tertiary set of contacts.

7. In a switch, the combination of a receptacle adapted to contain an insulating liquid, a primary set of contacts arranged to carry continuously a full load current flowing through a circuit, a secondary set of contacts, a tertiary set of contacts within 10 said liquid and means whereby said circuit is broken at said secondary set of contacts and made at said tertiary set of contacts.

8. In a switch, a movable contact and a substantially stationary contact adapted to 15 cooperate therewith, a second movable contact, and a contact adapted to cooperate therewith and mounted to follow and to maintain engagement with said second movable contact for a limited distance when the 20 same is moved to break the circuit, a third movable contact, and a contact adapted to cooperate therewith to follow said third movable contact for a limited distance after said third movable contact is separated 25 therefrom, whereby a circuit may be broken at said second movable contact and made at said third movable contact.

9. In a switch, a receptacle adapted to contain an insulating fluid, a movable contact and a substantially stationary contact adapted to cooperate therewith, a second movable contact, a contact adapted to cooperate therewith and mounted to follow and to maintain engagement with said second 30 movable contact for a limited distance when the same is moved to break the circuit, a third movable contact and a contact adapted to cooperate therewith to follow said movable contact for a limited distance after said 35 third movable contact is separated therefrom, all constructed and arranged whereby a circuit is broken beneath the surface of said liquid at said second movable contact and made beneath the surface of said liquid at said third movable contact.

10. In a switch, a receptacle adapted to contain an insulating fluid, a movable contact and a substantially stationary contact adapted to cooperate therewith, a second 40 movable contact a contact adapted to cooperate therewith and mounted to follow and to maintain engagement with said second movable contact for a limited distance when the same is moved to break the circuit, a third movable contact and a contact adapted to 45 cooperate therewith to follow said movable contact for a limited distance after said third movable contact is separated there-

from, all constructed and arranged whereby a circuit is broken beneath the surface of 50 said liquid at said second movable contact and made beneath the surface of said liquid at said third movable contact, and arc extinguishing means operative to extinguish the arc formed upon the separation of said 55 second movable contact and its cooperating contact.

11. In a switch, a receptacle adapted to contain an insulating fluid, a movable contact and a substantially stationary contact 60 adapted to cooperate therewith, a second movable contact, a contact adapted to cooperate therewith and mounted to follow and to maintain engagement with said second movable contact for a limited distance 65 when the same is moved to break the circuit, a third movable contact and a contact adapted to cooperate therewith to follow said movable contact for a limited distance after said third movable contact is separated 70 therefrom, all constructed and arranged whereby a circuit is broken beneath the surface of said liquid at said second movable contact and made beneath the surface of said liquid at said third movable contact, and 75 means forming an explosion chamber surrounding said second movable contact and its cooperating contact.

12. A switch comprising main current carrying contacts, secondary arcing contacts in 80 shunt therewith, means comprising other contacts in shunt with the main contacts for preventing burning of said secondary contacts when said switch is being closed, and means for rendering said means inoperative 85 when the switch is being opened.

13. A circuit controlling switch having main current carrying contacts, secondary contacts adapted to produce the final break in the circuit and means operable upon the 90 closing movement of said switch to shunt said secondary contacts.

14. A switch comprising main current carrying contacts, an explosion chamber, secondary arcing contacts therein connected in 95 shunt with said main contacts and arranged to produce the final break in the circuit, and means for preventing burning of said secondary contacts when said switch is closed, said means being located external of said explosion chamber and being connected in shunt with the secondary contact.

In witness whereof, I have hereunto set my hand this 22nd day of June, 1922.

JOHN D. HILLIARD.
